ABSTRACT

In a bobbin socket having a metal ring mounted between a bobbin body and a socket body, said ring has such a substantially S shape in vertical section that it can be integrally mounted to the upper and outer periphery of the socket body so as to protect the flange surface of the socket body from plastic deformations and damages which might otherwise be caused by the forced pressure of the lowest periphery of the bobbin body.

1 Claim, 2 Drawing Figures

PATENTED JAN 15 1974

3,785,585

FIG. 1

PRIOR ART

FIG. 2

1
BOBBIN SOCKET

The present invention relates generally to improvements in a socket provided with a substantially S shape metal ring for a spinning bobbin or yarn carrier, and more particularly it relates to such an improved type of socket means having a substantially S shape vertically sectioned metal ring to be adapted between a metallic spinning bobbin portion and a synthetic resin socket portion so as to secure the tightly connected relation between the socket and the bobbin.

For the purpose of securing a tightened connection of a socket to a spinning bobbin body it is customary to employ such a socket that its outer periphery is substantially same as, or a little greater than, the inner periphery of a lower bobbin portion thereby allowing the bobbin body to be fixedly mounted to a spindle through the socket thereby to enable the bobbin to carry out a spinning operation synchronously with the rotation of the spindle.

However, in order to tightly connect a socket body to a bobbin body, use is made for example of a hydraulic drive coupling means, a crank gear coupling means or a lever coupling means thereby mechanically forcing the socket portion into the bobbin portion so that the socket portion thus connected to the bobbin portion is easily pressed to undergo plastic deformations due to the great difference in strength between a socket material and a bobbin material. Consequently, in the above-mentioned method it is practically impossible to obtain a bobbin body that can be located accurately in center with respect to the spindle that rotates at a very high velocity thereby to rotate the bobbin body in synchronism therewith.

Accordingly, in order to maintain a tightened connection of the socket body to the bobbin body so as to locate the bobbin body accurately in center with respect to the spindle, it is customary to provide an upside-down U shape metallic ring between the two bodies thereby preventing the plastic deformations of the socket portion which might otherwise occur and at the same time enhancing the accuracy with which the bobbin body is kept in a concentric relation with respect to the spindle.

However, when such an upside-down U shape ring is adapted for mounting the socket body to the bobbin body, the upper and outer periphery of the socket body along which said ring is mounted is formed smaller in diameter than the lower and outer periphery of the socket body so that when the socket body is mounted to the bobbin body through said ring, there is caused a gap in the intermediate area intervening between said two peripheries, the result being that with the increased use of this type socket body as a means for mounting the bobbin body to a spindle, the tightened connection between the socket body and bobbin body is gradually loosened whereby the bobbin body deviates from the accurately centered position with respect to the spindle, consequently failing to bring about a satisfactory spinning effect.

Furthermore, along with the tendency of recent years demanding for yarn packages of a larger size, the metallic bobbin bodies have been increased in size so that especially when wound with a lower count yarn, the bobbin body becomes very heavy in weight as the whole.

2

Incidentally, in the case that such large-sized bobbin bodies to which each socket body is integrally mounted and on which a spinning yarn is wound to its maximum degree are manually handled for storage or transported by a vehicle or the like to succeeding spinning processes, they are not only given a great shock when placed in a storing place but also loaded henceforwards with unbearable dead weight in succession. Furthermore they must be subjected to incessant vibrations, 5 swinging frictions and impacts given thereto during the whole course of such vehicular transportation. Thus the socket portions exposed to such external forces are easily deformed or broken whereby the tightly connected relation between the socket body and the bobbin body is disconnected, giving rise to the deficiency that the socket body cannot serve any more. In this case, it may be thinkable to eliminate the above-mentioned deficiency by mounting a metallic ring to the socket portion so as to substantially remove or decrease the difference in strength of the material 10 between the bobbin portion and the socket portion directly connected thereto. However, it has been proved that such an upside down U shape ring serves only to strengthen the connected relation between the bobbin portion and the upside down U ring per se because of its configuration and the configuration of the bobbin portion which corresponds to the upside down U ring so that the connecting surfaces of the socket portion to the bobbin portion are subjected to the increasing frictions and plastic deformations because the socket material is by far smaller in strength than the ring material. 15

In view of all the above-mentioned difficulties and disadvantages, the present invention has been designed 20 to eliminate the same by providing for improvements in the conventional type of socket means for spinning bobbins.

Accordingly it is one of the main objects of the present invention to provide a socket body rigidly capped with a metal ring of a substantially S shape in vertical section thereby permitting the socket body to be connected to a bobbin body in integral relation.

It is another object of the invention to provide a socket body capped with a metal ring which is adapted 25 to receive the foremost end of a bobbin body in spaced relation with a socket portion thereby to prevent the socket body from plastic deformations and damages.

With the above and other objects in view, which will 30 become apparent in the following detailed description, the present invention will be clearly understood in connection with the accompanying drawing, in which:

FIG. 1 is a vertical section of a socket means coupled with a bobbin body which is shown with some parts broken away; and

FIG. 2 is likewise a vertical section of a conventional socket means in accordance with the prior art.

Now referring to the drawing, reference numeral 10 designates a socket body substantially composed of a plastic resin material. Said socket body 10 is comprised of a lower and inner periphery 11 having a connecting portion 12 to a spindle (not shown) substantially formed in a polygonal shape in cross section corresponding to the shape of the base portion of said spindle, a lower and outer periphery 13 thereof, and an upper and outer periphery 14 thereof which is smaller 35 in diameter than said periphery 13. Between said lower, outer periphery 13 and said upper, outer periphery 14

respectively of the socket body 10 there is formed a flange surface 15 defining the demarcation therebetween. The upper edge of said upper and outer periphery 14 is adapted so as to substantially form an upward semi-circular portion 16 in vertical section. Along the periphery of said upper edge thus formed there is fixedly mounted a J shape metal ring 17 subsequently described which constitutes the elemental part of the present invention.

Said metal ring 17 comprises a pair of inner and outer legs 17a, 17c, a curved bridge 17b and an extension member 17d. Said inner leg 17a is formed to correspond with the upper and inner periphery of the socket body 10 in contact therewith. Said outer leg 17c is longer in length than said inner leg 17a and is formed to correspond with the upper and outer periphery of the socket body 10 in opposed relation to said inner leg 17a. The curved bridge 17b has its both ends integrally terminating to said legs 17a, 17c and is formed into a semi-circular shape so as to correspond to said upward semi-circular portion 16. The extension member 17d extends outwardly from the lowest end of said outer leg 17c to an extent not exceeding the length by which said flange surface 15 extends radially outward of said socket body 10. Accordingly, the metal ring 17 thus formed presents a pair of substantially S shapes in vertical section as clearly shown in FIG. 1.

The metal ring 17 thus formed is tightly capped on said upward semi-circular portion 16 of the socket body 10 and then rigidly fixed thereto by punching the ring on some selected points of the peripheral surface thereof or in any other suitable fixing method.

A spinning bobbin body 18 may be of a conventional type of cylindrical or tubular form made from a metallic material, and comprises a lower portion 18' having the inner diameter of substantially same as, or a little smaller than, the outer diameter of the ring forming a true circle in cross section, and is so formed as to exactly correspond to said upward semi-circular portion 16 tightly capped with the ring 17.

Therefore, when the socket body 10 and the bobbin body 18 respectively formed in the above-mentioned manner are forcibly connected to each other for example by use of a hydraulic drive coupling means, a crank gear drive coupling means or the like, the peripheral edge of the lowest bobbin portion is brought into contact with the upper surface of said extension member 17d while the inner periphery of said lower bobbin portion is brought into pressed abutment against the outer periphery of the ring so that the load of the yarn wound bobbin body which works downward in the axial direction thereof is firstly frictionally received by said outer periphery of the socket body and then received therethrough the peripheral edge of the lowest bobbin portion which is brought into abutment against the upper surface of the extension member 17d. Furthermore, according to the metal ring 17 of the invention the extension member 17d is gently curved in the outward direction without contacting the flange portion 15 as has been mentioned, thereby defining a space between the bottom surface of the extension member 17d and the flange surface 15 opposing thereto so that the outer periphery of the socket body 10 is released from the whole load with which it might otherwise be burdened, consequently preventing the flange surface 15 from frictional deformations.

Incidentally, the cylindrical bobbin body 18 is obtained through the process in which a long length of metallic pipe formed in series is cut in one direction traversing the longitudinal axis thereof or along the outer periphery thereof thereby to form a plurality of desired lengths. Thus, with respect to the cross section of each cut length, at least both the outer semi-circumference and the inner semi-circumference opposing thereto are burried in the cutting direction, or otherwise the whole inner circumference of the length is burried along the cut edge. Due to the burrs thus formed, it is inevitable that the outer periphery of the ring should be scratched by the inner periphery of the lowest bobbin portion when they are forcibly connected to each other, consequently making it quite impossible to secure such a tightened connection of the socket body to the bobbin body that can maintain the bobbin body in the exactly centered position with respect to the spindle.

Therefore, in order to eliminate the above-mentioned deficiency it is customary that each edge of cut length is pared away as is shown in FIG. 1. In this case, in the conventional bobbin socket shown in FIG. 2 which has an upside down U shape ring 17' mounted thereon, it will be easily understood that the pared lowest peripheral end 19 is forcibly and directly thrusted into the socket flange 15', thus causing undesired plastic deformations thereof. However, according to the present invention, the metal ring 17 capped on the upper peripheral edge of a socket body 10 shown in FIG. 2 comprises two legs 17a, 17c, curved bridge 17b and to extension member 17d gently curved at the end of said leg 17c and extended outwardly in perpendicular relation thereto or radially outward of the socket body 10 so as to be spaced away from the flange surface 15 defining the demarcation between the upper, outer periphery and the lower, outer periphery of the socket body 10 thereby giving a slight resiliency to said extension member 17d.

Accordingly, even if the upper surface of the extension member 17d is forcibly pressed by the aforesaid lowest end of the bobbin body 18 which is pared off along the outer and inner peripheral edges thereof, it can resiliently receive said lowest end whereby the flange surface 15 of the socket body 10 is always kept free from any deformations and damages.

The last but not the least, it is desirable that the extension member 17d is provided substantially shorter in length so that when a sleeve 20 is mounted onto the bobbin body 18 and the socket body 10 integrally connected thereto, the forward end of the extension member 17d should not scratch the inner periphery of the sleeve 20.

In view of the above, several advantages of the present invention, it is to be understood that the above-mentioned embodiment is given by example only and not in a limiting sense.

I claim:

1. In a bobbin socket for holding a bobbin comprising a synthetic resin cylindrical socket means, said socket means including coaxial cylindrical upper and lower portions, said lower portion having an outer peripheral surface diameter which is larger than the outer peripheral surface diameter of said upper portion, a flange portion formed by the top of said cylindrical lower portion and extending between the outer peripheral surfaces of said upper and lower portions in a concentric

relation therewith, a vertically semi-circular sectioned annular edge portion formed on the top of the upper portion of said socket means, and an annular metal ring means covering said annular edge portion, the improvement wherein said ring means comprises:

a vertically semi-circular sectioned annular ring section corresponding in shape and extending circumferentially around said edge portion, an external ring section extending circumferentially around the outer peripheral portion of the upper section of said socket means, and an internal ring section extending circumferentially around the inner peripheral portion of the upper section of said socket means, said external ring section being substantially longer in length than said internal ring section

5

10

15

and having an extension section extending radially outward to an extent not exceeding the length by which said flange portion extends from the upper portion of said socket means, said ring means thereby forming as a whole a substantially S shape vertical cross-section, said extension section being formed to support on the upper surface thereof the lowest end of the bobbin and said external ring section being shorter in length than the length of said upper portion to define a space between the bottom surface of said extension section and the surface of said flange portion opposite to the bottom surface of the bobbin.
